UNITED STATES PATENT OFFICE.

JAMES C. KENNEY, OF YOUNGSTOWN, OHIO.

GUARD FOR POWER-OPERATED MACHINES.

1,152,106.

Specification of Letters Patent. Patented Aug. 31, 1915.

Application filed May 13, 1914. Serial No. 838,312.

To all whom it may concern:

Be it known that I, JAMES C. KENNEY, a citizen of the United States, residing at Youngstown, in the county of Mahoning, State of Ohio, have invented certain new and useful Improvements in Guards for Power-Operated Machines; and I do hereby declare the following to be a full, clear, and exact description of the invention, such as will enable others skilled in the art to which it appertains to make and use the same.

This invention relates to a guard for power operated machines and more particularly for the class of machines which employ reciprocating operating parts.

An object of the invention is to provide a device of this character which will be thrown into such position when the machine is started as to prevent access to the operating parts.

A further object of the invention is to so construct a guard that it will protect the operator when the guard is in its uppermost position.

With these and other objects in view, such as will appear as the description progresses, my invention comprises the combination and arrangement of parts as herein set forth and subsequently claimed.

Referring to the drawing, Figure 1 is a front view of my device applied to a shearing machine. Fig. 2 is a side view thereof. Figs. 3 and 4 are fragmental details.

Referring to the drawing by reference characters wherein like parts are indicated by like characters throughout the several views, 1 indicates the frame of the machine on which the main drive shaft 2 is mounted which has a driving gear 3 and a clutch 4 for fixing the gear to the shaft. Operated by the said shaft 2 is a shearing blade 5 which reciprocates upward and downward during the operation of the machine and co-operates with a blade 6 on the bed of the machine, which latter blade is located on the inner portion of the work support 7.

Pivoted to each end of the machine is a lever 8, pivoted as at 9, to the frame of the machine. The long arms of these levers extend forwardly beyond the forward face of the cutting blade 6. The forward ends of the said levers being adjustably secured by set screws 10 to sleeves 11 on links 12 secured to the standards 13' by bolts 12' in-

sertible in holes 12" by means of which the links are longitudinally adjustable on the standards. The standards have slots 13 on their inner faces extending throughout their lengths. These slots communicate with longitudinally extending holes 14, the purpose of which will be hereinafter apparent.

A rectangular frame 15 having braces 16 and a wire screen 16' secured thereto extends between the standards 13' and on each end of the said frame is an elongated extension 17 which extends through a slot 13 and has an enlarged head 18 on the end thereof, which extends upwardly and downwardly in the hole 14 in the adjacent standard.

In order that the heads 18 may be held within the holes in the standards 13' there is provided on the upper ends of the heads a pair of hooks 19 which embrace the sides 75 of the standards and are engaged with coil springs 20 fixedly mounted at their lower ends by means of hooks 21 to the lowermost portions of casings 22 which are secured longitudinally of the standards 13' and attached thereto. In the inner faces of these casings slots 23 are formed which extend longitudinally of the said casings and through which the hooks 19 extend and are adapted to reciprocate.

On the inner faces of the standards 13' adjacent the lower ends thereof are formed lugs 24 which co-operate with lugs 25 on the ends of the frame 15 to limit the downward movement of the said frame with relation to the standards.

The rearmost arm 26 of each of the levers 8 is attached to a link 27, which link is pivotally secured to a treadle 28 having a counterweight 29 on one end thereof and a foot piece 30 secured to the forward end thereof and extending to the other of said treadles.

A clutch operating arm 31 is pivotally secured at 32 to the forward arm of the lever 8 and is attached to the clutch 4 on the drive shaft 2 so as to operate the same.

When the guard is in its operative position, such as shown in dotted lines in Fig. 2, the lower ends of the standards 13' contact with the upper face of the work support 7 and the frame on which the wire mesh is secured extends between said standards, the springs 20 having been extended by the contacting of the lower ends of the heads 18 with the upper face of the work support. The device assumes this position when the device is in operation.

Assuming that the guard is in its uppermost position, as shown in full lines in Fig. 2, the clutch is disengaged and the machine is at a position of rest. If it is desired to operate the machine the foot piece 30 is pushed downwardly, which rotates the treadle 28 about its pivot and pushes the link 27 upwardly, this rotates the lever about its pivot and moves the frame 15 downwardly, and at the same time the rod 31 is operated to throw in the clutch which causes the machine to start, the downward movement of the guard is in advance of the downward movement of the cutting blade 5 so that access will be prevented from the said cutting blade during the operation of the machine. When the lowermost portion of the frame 15 contacts with the upper face of the work support 7, the portions 18 of the said frame which are slidably mounted in the standards 13 are pushed upwardly therein against the tension of the springs 20, and the lowermost portion of the standards contacts with the upper face 25 of the work support on the further movement of the treadle. During this position of the guard it is impossible for the operator to insert his hands or other parts of his body in the line of movement of the reciprocating parts of the machine. After the operation has been completed the foot piece 30 of the treadle 28 is released and the weight 29 on the opposite end thereof pulls the link 27 downwardly, which rotates the levers 8 about their pivots 9 so as to move the forward ends of the levers upwardly and with them the guard members, and at the same time the rod 31 is moved outwardly and throws out the clutch so that the machine stops a little in advance of the upward movement of the guard. When the guard is moved upwardly the springs 20 exert pressure on the hooks 19 so as to pull the frame 15 downwardly, and this extends the 40 said frame below the standards 12. The downward movement of this frame is limited by the contacting of the lugs 24 on the standards and of lugs 25 on the frame. By projecting this frame downwardly in this 45 manner, the device still operates to guard the operating parts, inasmuch as the distance between the work support and the lower end of the frame 15 is just sufficient to allow the work to be inserted therebetween.

From the foregoing description it may be seen that I have provided a device which will effectively guard a machine, the parts

of which reciprocate so that the operator may not be injured by inserting parts of his body in the line of movement of the reciprocating parts.

I have still further provided a device which will prevent access to the said reciprocating parts of the machine during the 65 operation of the machine, and which will also act as a guard during the inserting of the work into the operating parts.

While I have described my device as attached to a particular type of machine, I 70 wish it to be understood that it is only illustrated as attached to that type of machine for the sake of convenience, for I wish to reserve the right to use it in connection with any machine wherein the parts are 75 movable in such a manner that if an operator insert his hands or other parts of his body between the operating parts he will receive injury.

What is claimed is:—

1. In combination with a machine having reciprocating parts, a guard pivoted thereto, said guard comprising hollow elongated standards having slots in their inner faces, a frame extending between said standards 85 and secured thereto, heads formed on the ends of said frame and slidably mounted in the standards, hooks secured to said heads, springs secured to the standards at their lower ends and at their other ends to 90 the hooks, casings for said springs, and means to limit the movement of the frame with relation to the standards in one direction.

2. In combination with a machine having 95 a reciprocating tool and a work support, levers pivoted to the opposite sides of said machine and adapted to swing in vertical planes, standards secured to the forward ends of said levers, a rectangular guard 100 slidably mounted between and supported by said standards, resilient means for causing said guard to extend downwardly from the lower ends of said standards when the latter are raised and means for moving said 105 levers in such manner that the standards will be lowered and the guard moved upwardly therein until the lower ends of the standards engage the work support.

In testimony whereof, I affix my signature, in the presence of two witnesses.

JAMES C. KENNEY.
